OF NEW JERSEY.

MIXING DEVICE FOR FLUIDS.

1,110,223.

Specification of Letters Patent.

Patented Sept. 8, 1914.

Application filed April 11, 1911. Serial No. 620,480.

To all whom it may concern:

Be it known that I, THOMAS W. MORSE, a citizen of the United States, residing at Paterson, in the county of Passaic and State of New Jersey, have invented certain new and useful Improvements in Mixing Devices for Fluids, of which the following is a specification.

This invention relates to a device particularly adapted for thoroughly mixing two or more elements either in a finely divided or a fluid state, and while particularly adapted for the intermixing or intermingling of air and fluid or gaseous fuel subsequently to be utilized for the production of light, heat or power, is not necessarily limited thereto as the device might be used for mixing various other materials.

The principle of the invention is particularly well applied to mixing devices such as are used in combination with carbureting devices in order to more thoroughly mix or commingle the elements which issue from the delivery port of a carbureter before their introduction into an explosive engine.

The general object of my invention is to secure the greater homogeneity and reduce stratification of mixtures of air and liquid fuel and secure an intimate intermingling of the component parts of the mixture. The interposing of baffles or intermingling elements against which the liquid particles may impinge, tends toward the securing of this result but the increasing of these elements to such an extent as to produce a material area of impact surface impedes the progress of the mixture to an objectionable extent. The simple swirling of the mixture is of very little effect and the use of fans or other moving parts for breaking up and intermingling the component parts is efficient if operated mechanically but possesses the objection that it includes moving parts which require attention or they are liable to get out of order. In carrying out my invention I produce a swirling of the mixture so that the parts thereof travel in a helicoidal path and impinge or strike spaced intermingling elements at an angle to the plane of such elements. Thus these elements may be spaced a sufficient distance apart to permit the free passage of the mixture between them but at the same time will lie in the path of the maximum amount of the component parts of the mixture. The

transverse area of the passage in the plane of the intermingling elements may be greater if desired than the transverse area of the other portions of the passage. Thus there may be greater free space through the plane of the intermingling elements than at other points along the path, but the swirling of the mixture as it encounters the elements brings all of the elements into contact with the rapidly moving mixture. Furthermore the component parts of the mixture in being deflected by the intermingling elements become more thoroughly mixed entirely aside from a shattering action on the liquid particles.

A further important feature of my invention involves the producing of an increased swirling action upon a decrease in pressure in the conduit. This I may accomplish by forming the helicoidal passage with a comparatively shallow part directly opposite to the outlet from the device. The fluid in being drawn directly from this shallow portion is replaced by the entering fluid, which to fill the void takes on an increased swirling movement due to the conformation of the walls of the passage.

A specific embodiment of my invention is shown in the accompanying drawings wherein:

Figure 1 is an elevation of a plurality of explosive engines connected by a manifold to a carbureter, my improved mixing device being disposed between the manifold and the carbureter. Fig. 2 is a partly sectional view on the line 2—2 of Fig. 4, the main portion of the chamber being in elevation. Fig. 3 is a sectional view of the mixing chamber on the line 3—3 of Fig. 4. Fig. 4 is a plan view of the end wall of the mixing chamber. Fig. 5 is a perspective view of the lower section or end wall of the mixing chamber looking downward from above, and Fig. 6 is a sectional view of the lower member of the casting taken on the line 6—6 of Fig. 4.

My improved mixing device includes a mixing chamber 2, circular in plan or section, and having therein a vortex producing surface 3 forming in the embodiment of my invention disclosed the inner surface of the end wall 4 of the mixing chamber. This vortex producing surface 3 is so formed as to cause the fluid passing through the mixing device to travel in an approximately helicoidal path. The end wall 4 is

formed with an inlet port 5 which forms the inner extremity of an inlet passage 6. The axis of this passage is tangential to the circumferential wall 7 of the chamber, and, as will be seen from Fig. 2, this passage extends at an acute angle to the outer face 8 of the end wall. From the point where the inlet passage 6 enters the chamber, that is, from the port 5, the surface of the end wall approximates the contour of part of one convolution of an expanding helicoid, the surface extending upward from the inlet opening and around the chamber, the approximate center of the helicoid being at the point X in Fig. 4 and hence eccentric to the axial center of the chamber. It will be seen from Fig. 4 that the surface 3 of the end wall is a gradually widening helicoid and that radii drawn from the center X to the side wall gradually get longer and longer, the longest radius being the radius Y extending diametrically across the chamber. From there on, the radii get shorter and shorter.

It will be observed from the inspection of Figs. 2, 3, 4 and 5 that the contour of the surface 3 is such that there is a relatively deep inlet portion 9 of the chamber, and that from this inlet portion the surface 3 sweeps around and upward, gradually and continuously decreasing in pitch, in such manner as to cause a smooth and gradual change in the direction of flow of fluid passing thereover.

Located within the body 2 of the mixing chamber are one or more spaced intermingling members 10, these members preferably forming a wire screen of relatively large mesh, the members acting to break up and intermingle the particles of air and gasoline impinging against the screen or screens. Preferably, I use a plurality of screens, spaced from each other as shown in Fig. 3, but I do not wish to confine myself to this feature. Preferably, also, I use wire screen material as a means for thoroughly intermingling the particles of air and fuel but I do not wish to limit myself to this as it is obvious that other elements crossing the chamber 2 may be used for the same purpose.

It will be seen that with this construction the charge entering through the port 5 will strike against the wall 7 and will be given a circular movement, while at the same time the helicoidal surface 3 will cause a smooth and gradual change in the direction of the flow of the fluids passing thereover, and that this change in direction of the flow will cause the fluid to impinge against the mixing or intermingling elements 10 at an extremely acute angle to the general surface of the screens. As a consequence, the particles of air and gasoline will be deflected in their course and will fly off in all

directions, thereby causing a more uniform mixture of the elements of which the charge is composed. Furthermore, it will be seen that by causing the fluid to be directed at an acute angle to the surface of the mixing screens, all portions of the charge will be caused to impinge against the wire elements of the screens. If the charge passed directly upward through the screens at right angles to the general surface of the screens, a large portion of the charge would not strike the cross wires of the screens at all, and the charge would therefore not be as well mixed or intermingled as it would be if the charge were directed at an acute angle to the screen. It will be seen that the screens therefore cut the path of travel of the particles of the charge at an acute angle, the charge not only traveling toward the screens at an acute angle but also swirling.

An important factor in my invention resides in the fact that the reduction of the area of the inlet port, as in the case of the closing of the throttle (located at or below said port) which relatively increases the vacuum tendency resulting from piston suction, tends to relatively increase the rotary speed of the swirling charge, thus maintaining approximate constancy of disintegration, diffusion and admixture under varying throttle conditions such as occur in motor vehicle operation. For instance, with the volume throttled to a minimum, the entering charge will be drawn toward the shallowest portion of the chamber and the whirling motion of the charge will relatively increase.

My invention is simple, compact, may be easily applied to all forms of motors and I have found it in practice to be thoroughly effective, as it increases the efficiency of the ordinary type of internal combustion motor by making possible the development of heat units more rapidly and in greatly augmented volume, and through the homogeneity of the mixture, causes constancy in flame propagation of successively ignited charges, increasing the power and thermal efficiency of the motor and reducing torque vibration.

What I claim is:—

1. A mixing chamber circular in plan having substantially an entire end wall inclined from the sides of the chamber to an inlet passage disposed at the deepest portion of the chamber, and entering said chamber tangential to the circular wall of the chamber.

2. A mixing chamber having a series of spaced commingling elements extending across the same, the end wall of the chamber opposed to said commingling elements having the contour of one convolution of a gradually expanding helicoid, the axis of which is eccentric to the axis of the mixing chamber, the mixing chamber being formed

with an inlet opening disposed at the initial termination of the helicoid.

3. In a mixing device, a mixing chamber provided with an end wall and having an inlet passage opening through said end wall, entering said chamber tangentially, and entering the mixing chamber at an acute angle to the outer surface of the end wall, and a screen of spaced elements extending across the chamber at right angles to the axis thereof, the inner surface of the end wall having a helicoidal contour, the axis of the helicoid being eccentric to the axis of the chamber and said surface gradually and continuously approaching the screen as it extends from the inlet opening.

4. In a mixing device, a mixing chamber, spaced commingling elements disposed within the chamber and extending across the same in a plane at right angles to the axis of the chamber, said chamber having a surface opposed to the commingling elements, said surface having the contour of one convolution of a helicoid, the axis of which is eccentric to the axis of the chamber and formed with an inlet passage opening at the initial point of said helicoid, the pitch of the helicoidal surface constantly decreasing from said initial point.

5. A circular mixing chamber having an end wall whose inner surface approximates a portion of a convolution of an expanding helicoid and having an inlet opening disposed between the terminations of the helicoid, said opening having a diameter approximately equal to the diameter of the initial portion of the helix, and the mixing chamber having an outlet larger in area than the inlet.

6. A device for use in the intake pipes of internal combustion engines, said device being located between the carbureter and the engine, and acting upon the explosive mixture passing to the engine, for rendering the latter more homogeneous and including a series of interfering or commingling elements extending across said intake pipe and each disposed in a plane extending approximately at right angles to the axis of the adjacent portion of the intake pipe, said elements being of such size and so spaced as to not materially reduce the cross-sectional area of the passage in the plane of said elements, and a fixed obliquely inclined wall closely adjacent to said elements for giving a swirling movement to the mixture and di-

recting it toward said interfering elements in a direction at an acute angle to the plane of the latter to break up drops of liquid fuel, as said drops strike said elements.

7. A device for use in the intake pipes of internal combustion engines, said device being located between the carbureter and the engine, and acting upon the explosive mixture passing to the engine, for rendering the latter more homogeneous, and including a series of interfering or commingling elements extending across said intake pipe, said elements being of such size and so spaced as to not materially reduce the cross-sectional area of the passage in the plane of said elements, and a fixed obliquely inclined wall closely adjacent to said elements for giving a swirling movement to the mixture and directing it toward said interfering elements in a direction at an acute angle with the plane of the latter to break up drops of liquid fuel, as said drops strike said elements.

8. A device for use in the intake pipes of internal combustion engines for rendering homogeneous the explosive mixture from the carbureter comprising a mixing chamber having spaced interfering elements extending across the chamber and a fixed deflecting member having a helicoidal surface at the inlet portion of said chamber and serving to impart to the fluid a swirling movement as said fluid passes said interfering elements.

9. A device for use in connection with combustible gaseous mixture supply pipes for rendering more homogeneous said mixtures and including means for swirling the mixture and a series of spaced impact interfering elements extending at an acute angle to the path of the mixture and substantially at right angles to the axis of the supply pipe.

10. A device for rendering more homogeneous gaseous mixtures containing liquid particles, comprising a stationary helically disposed wall for swirling the mixture about the axis of the device and a series of impact or interfering wires forming a screen and extending in a plane transverse to the path of the mixture at the delivery side of said helically disposed wall.

In testimony whereof, I affix my signature in presence of two witnesses.
